ELECTROMAGNETIC ACTUATOR

Leland E. Lawrence, Wauwatosa, Wis., assignor
to Allen-Bradley Company, Milwaukee, Wis., a
corporation of Wisconsin

Application June 16, 1952, Serial No. 293,791

24 Claims. (Cl. 200—104)

1

This invention relates to an electro-magnetic actuator suitable for causing motion for such purposes as the opening and closing of switch contacts, the operation of valves and other mechanical instrumentalities, and it more specifically resides in an actuator having a coil, a yoke extending along the exterior of the coil and an armature extending through the coil in mutually attractive relation to the yoke, the armature being smaller in cross section than the inside opening of the coil and being guided for translatory movement in parallel attitudes across the axis of the coil in response to energization of the coil.

For many purposes, particularly for the actuation of switches having preloaded spring backed contacts, it is desirable that the magnet employed not stop in its closing movement after initial engagement of the contacts and prior to sealing of the magnet. To avoid partial closure it is important that an electro-magnetically actuated switch have pull-in characteristics such that motion to sealed position is inevitable at any voltage equal to or in excess of pickup voltage. To this end it is desirable to provide a magnet in which pickup voltage is or can be made comparable to, or greater than the voltage required for the magnet to overcome the maximum opening forces encountered during compression of the contact springs.

Actuating electro-magnets also are in essence single stroke electric motors which usually are called upon to function over a long life without lubrication. It is desirable therefore that rubbing surfaces, subject to wear, employed to guide the motion of the parts be as lightly loaded as possible. To this end it is important to not impose upon the wearing surfaces of the guides employed forces arising from directly acting magnetic attraction.

It is desirable also that an electro-magnet be compact in relation to its power; that it be simple, economical and rugged in its construction; and that it be versatile in that it may be modified without undue expense to meet the requirements of various loads to be actuated.

With these and other considerations in view an electro-magnetic actuator is provided in accordance with this invention in which an armature is mounted in a coil wound large enough to permit motion of the armature across the axis of the coil and an external yoke running along the outside of the coil is disposed to gather flux to cause an attractive force to be exerted on the armature in the direction of movement of the armature which for convenience herein is referred to as transverse movement, the whole being com-

2

bined in novel fashion with guiding means which engage the ends of the armature and join with parts which transmit the actuating force.

It is an object of this invention to provide an electro-magnetic actuator in which the attractive force between yoke and armature due to the magnetic field, in open position, is opposed by a magnetically induced force which diminishes to a negligible quantity as the magnetic actuator moves to closed position.

It is another object of this invention to provide an electro-magnetic actuator in which the armature is disposed within a coil and is translated transversely and in a straight line to a sealed position with a yoke which it meets at two sets of sealing surfaces through which the total working flux passes when the magnet is closed.

It is still another object of this invention to support an armature in the central opening of a coil for movement in a straight line in parallel attitudes transversely of the coil opening.

A further object of this invention is to diminish the side play and end play of the armature of an electro-magnet by the provision of bearing surfaces that maintain the alignment of the armature with respect to the yoke within narrow limits.

Another object of this invention is to provide a magnet in which side pull on the armature is relatively small so as to reduce wear of the armature guiding means.

It is a further object of this invention to provide a supporting and guiding structure for an armature for guiding the movement of the armature and for transmitting such motion to the movable contacts of an electro-magnetic switch.

It is another object of this invention to provide a yoke and armature capable of limited accommodating movement with respect to one another about two perpendicular axes, to permit self alignment of the sealing surfaces between them.

It is a further object of this invention to provide an arc hood for an electro-magnetic switch of the class described, which arc hood includes stationary contact assemblies that may be removed to expose the same for inspection.

These and other objects and advantages will appear in the description to follow. In the description reference is made to the accompanying drawings which form a part hereof and in which there is shown by way of illustration and not of limitation certain specific embodiments of this invention.

In the drawings:

Fig. 1 is a front view in elevation with parts broken away and in section of an electro-mag-

netic switch in which this invention may be embodied.

Fig. 2 is a side view in cross section of the electro-magnetic switch shown in Fig. 1 viewed through the plane 2—2.

Fig. 3 is a front view in elevation with parts broken away and in section of the electro-magnetic switch shown in Figs. 1 and 2 with the armature thereof in sealed or closed position.

Fig. 4 is a fragmentary front view in elevation with parts broken away and in section of a modification of the electro-magnetic switch shown in Figs. 1, 2 and 3 having a supplementary yoke positioned beneath the armature.

Fig. 5 is a perspective view of the magnetic yoke of the electro-magnetic switch shown in Figs. 1, 2 and 3.

Fig. 6 is a perspective view of the field support member of the electromagnetic switch shown in Figs. 1, 2 and 3.

Fig. 7 is a perspective view of the magnetic armature of the electro-magnetic switch shown in Figs. 1, 2 and 3.

Fig. 8 is a perspective view of the armature carrier of the electro-magnetic switch shown in Figs. 1, 2 and 3.

Fig. 9 is a perspective view of the magnetic yoke and the magnetic armature of the switch shown in Figs. 1, 2 and 3 in open position and with the actuating coil schematically represented in its position relative to the yoke and armature, and

Fig. 10 is a perspective view of the magnetic components of the modification of Fig. 4 with the actuating coil schematically represented.

Referring now to the drawings and more particularly to Figs. 1, 2 and 3, there is shown therein an electro-magnetic switch 1 which comprises a base plate 2 on which is mounted an actuating unit 3 and a stationary contact unit 4. Forming the body of the actuating unit 3 is a field support member 5 composed of a right hand half shell 6 and a left hand half shell 7. The shells 6 and 7 each have a back wall 8 that abuts the base plate 2 and a front wall 9. Bottom walls 10 integrally join the walls 8, 9 at the respective base portions of each and middle wall portions 11 bridge the respective walls 8, 9 at a point below the tops thereof. With the shells 6 and 7 against one another, as is more clearly shown in Fig. 6, a window opening 12 and an upper trough like portion 13 are formed that extend through and across the width of the field support member 5.

The facing surfaces of the shells 6 and 7 are recessed to provide an enclosed cavity 14 that extends about the window 12 and which is shaped to closely receive an actuating coil 15. The coil 15 is of tubular configuration and is comprised of roughly concentric turns wound to conform to the shape of the cavity 14. Terminals 16 and 17 are attached to the coil 15 and extend from within the cavity 14 through appropriate slots in the front walls 9 of the field support member 5 to the exterior, thus providing convenient means for the attachment of energizing leads which are not shown. The coil may be fixed within the cavity of the field support member 5 by forming it of such size as to fit snugly within the cavity so as to require no further support, as shown, or the coil may be cemented or potted in the member 5 to give greater support and to improve heat dissipation.

The right hand and left hand shells 6 and 7 are secured to one another so as to form a

unitary member 5 by bolts 18 or other suitable fastening means passed therethrough. The member 5 is oriented with respect to the base plate 2 by tongues 19 which project rearwardly from each back wall 8 to be received snugly within a rectangular opening 20 near the bottom of the plate 2.

Disposed within the trough like portion 13 of the member 5 is a stationary inverted U-shaped magnetic yoke 21 having downwardly extending legs overhanging beyond the sides of the half shells 6 and 7. The yoke 21 is comprised of a plurality of magnetic laminations 22 stacked in two groups that are separated by an air gap 23 extending for the full width of the magnetic portion of the yoke 21 so as to interrupt the flux path. Disposed at either side of the stacked laminations 22 is one of a pair of side plates 24 bound in place by rivets 25 which extend through the laminations 22 and the side plates 24 to clamp the yoke elements tightly to one another. The plates 24 are formed thick enough to have adequate strength to maintain the tightly compressed relation of the laminations 22 and preferably are formed of a material that will not provide a flux path shunting the air gap 23. High reluctance stainless steel has been found to be a material adequate for this purpose.

The two downwardly facing end surfaces 26 at the lower ends of the legs of the U-shaped yoke 21 are disposed slightly beneath the middle wall portions 11 that form the upper limit of the window opening 12. Each of the surfaces 26 is slotted to receive a shading coil 27 and the surfaces 26 are ground flat and coplanar to provide a pair of sealing surfaces against which the armature of the electro-magnetic actuator may rest or seal upon attraction of the armature toward the yoke 21.

A mounting bolt 28 provided with a lock washer is passed through the front walls 9 of the member 5 and thence through the yoke 21 and the rear walls 3 of the member 5 from which the threaded end emerges to be received in a tapped hole 29 in the base plate 2. The bolt 28 may be of magnetic material in which case its diameter should be small enough to leave a suitable air gap between it and the two lamination stacks 22 that will maintain the effectiveness of the air gap 23. Drawn up tightly, bolt 28 acts as a single fastening which secures the entire assembled field structure comprising the support member 5, the coil 15 and the magnetic yoke 21 in place. As shown in Figs. 2 and 3 the bolt 28 supports the yoke 21 in a position such that there is a perceptible clearance between it and the half shells 6, 7 to permit the yoke 21 when acted upon by a sufficient force to overcome the clamping friction applied by bolt 28 to pivot slightly. The plane of the seal surfaces 26 is thus capable of limited accommodating movement about the axis of the bolt 28 when sufficient force is applied for purposes to be hereinafter described.

Carried by and in slidable engagement with the field support member 5 is a stirrup shaped armature carrier 30 that extends around the outside of the coil 15 and straddles the yoke 21. The configuration of the carrier 30 is shown more clearly in Fig. 8. The carrier 30 is a unitary integral insulating element comprising primarily, a contact carrying horizontal cross bar portion 31, and two downwardly extending legs 32. A pair of notches 33 let into the cross bar 31 slidably fit closely about tongues 34 that project

5

from the front walls 9 and back walls 8 of the field support member 5, as is shown in Fig. 6. The notches 33 and tongues 34 slidably engage one another to provide upper alignment guides for the carrier 30 that restrict movement to a vertical straight line action. The lower ends of the legs of the armature carrier 30 are turned inwardly to terminate in spaced pads 35 which bear with a freely sliding fit against the sides of the bottom walls 10 of the field support member 5. The pads 35 are retained against side-wise movement by projections 36 formed as an integral part of the member 5. A set of lower alignment guides is thus provided, which in conjunction with the upper alignment guides mounts the carrier 30 for non-binding vertical movement.

Fitted between the lower portions of the legs 32 of the armature carrier 30 is a magnetic armature 37 that extends through the window opening 12 of the member 5. Downwardly projecting tenons 38 formed as a part of the armature 37 below the slots 39, form a dovetail connection between the pads 35 and ribs 40 to provide a loose but permanent connection between the carrier 30 and the armature 37. The metallic parts making up the magnetic circuit of the actuating unit 3 are called upon to perform no part in the guiding of the armature carrier and contact assembly. The armature 37 is located longitudinally by the armature carrier 30 and is approximately centered in it laterally by the back wall 8 and front wall 9 of field support member 5 which form two sides of window 12. Walls 8 and 9 are so spaced as to permit free motion of armature 37 toward and away from yoke 21. By forming the carrier 30 and field support member 5 of a material such as phenol-aldehyde resin or the like, dry bearing surfaces can be provided that will give long life with only small amounts of wear.

The armature 37 is thus mounted to move transversely with respect to the axis of the coil 15. The carrier 30 and armature 37 form an assembly which moves as a unit whenever the armature 37 is moved upward in response to magnetic attraction between the armature 37 and the yoke 21. Likewise, a release of the armature 37 from closed or sealed position with respect to the yoke 21 causes downward movement in unison of both the armature 37 and carrier 30. The downward travel is arrested when the bottom surface of the armature 37 contacts the upper surface of the bottom wall 10. The molded armature carrier 30 is thus relieved of the direct impact stresses arising out of the arresting of downward travel of the armature upon deenergization. Such stresses are instead absorbed by the field support member 5 and the armature 37. The amount of vertical travel of the armature 37 and carrier 30 is dependent upon the vertical distance between the faces 26 of the yoke 21 and the upper surface of the bottom wall 10 and the armature thickness between these two surfaces. The mating guide surfaces for the armature carrier 30, which are part of the notches 33 and tongues 34 and of the pads 35 and projections 36, overlap one another by an extent greater than the amount of armature travel to ensure that the carrier 30 is captively retained in all operating positions. The extent of overlap of the guide surfaces is related to the downward extent of the seal surfaces 26 of the yoke 21 below the middle wall portions 11. The extent of downward extent of seal surfaces 26 must be greater than the overlap of the guiding surfaces so that upon removal of the bolt 28 the armature 37 and

6

carrier 30 and yoke 21 may be moved upwardly to disengage the guiding surfaces to permit assembly and disassembly.

The armature 37 is composed of a stack of laminations 41 of ferro-magnetic material providing a low reluctance flux path. A pair of side plates 42 are placed at the sides of the laminations and rivets 43 disposed as shown hold the laminations 41 and the side plates 42 in place. The upper surface 44 of the armature 37 is ground flat and is slotted at 46 over the areas facing and in alignment with the shading coil slots. Similar slots 46 in alignment with the inner edges of the yoke sealing faces 26 set off and define a pair of armature sealing faces 45 that seal against the surfaces 26 of the yoke 21 when the armature assembly is raised to closed position. The working flux circuit comprises a single loop or path that intersects each of the sealing surfaces so that separation of either pair of surfaces interrupts the entire working flux.

As has been noted, the yoke 21 is permitted a limited accommodating movement about the mounting bolt 28 when sufficient force is applied. This force is ordinarily provided by impact of the armature upon sealing. Lateral alignment of the seal surfaces 26 with the seal faces 45 is thus brought about as a normal function of the magnet. To provide for transverse alignment, that is to permit the armature to rotate about a horizontal line perpendicular to the bolt 28, the armature 37 is mounted loosely in the carrier 30 with sufficient clearance to permit it to rotate slightly to seal against yoke 21 without communicating a corresponding binding motion to the carrier 30. Because of this freedom of accommodation and because of the near absence of any magnetic side pull which can be communicated to the carrier 30, the carrier 30 moves with a minimum of friction and wear.

Comprising an integral part of the cross bar portion 31 of the armature carrier 30 is an upwardly extending rib 46 through which extend four openings 47. A movable bridging contact 48 is extended through each opening 47 and a contact spring 49 compressed between each contact 48 and the cross bar 31 retains the contacts 48 in an upper position. Movement of the armature 37 from open to closed position causes a like movement of the bridging contacts 48 which are brought into engagement with stationary contacts to be described.

Extending outward from the base plate 2 and over the actuating unit 3 is an arc hood 50 tightly secured by a pair of mounting bolts 51. The hood 50 is formed with a rear wall 52 from which extend in a forward direction side walls 53 at either end of the wall 52 and three partition walls 54 spaced evenly between the end walls 53. A front wall 55 extends across the forward ends of the walls 53, 54 to provide four open bottomed arc restricting chambers, each chamber being adapted to receive one of the movable bridging contacts 48. Enclosing the top of the hood 50 are four contact mounting terminal boards 55, each being disposed directly above a bridging contact 48. A rear contact 56 and a front contact 57 are riveted to each terminal board 55 so as to be engageable with the respective bridging contact 48 disposed in alignment therewith. The contacts 56 and 57 each terminate in convenient terminals 58 and 59 and mounting screws 60 extending through each of the terminals 58 into an engaging nut 61 maintain the terminal boards 55 in place. Thus, there is provided a

unitary sub-assembly for each set of stationary contacts that may be easily removed from and inserted in the arc hood 50 for such purposes as inspection or replacement of contacts.

In Fig. 4 there is shown a modification of the switch of Figs. 1, 2 and 3 that has a supplementary magnetic yoke extending beneath the coil. Like parts of the modified switch of Fig. 4 and the switch of Figs. 1, 2 and 3 are designated by like reference numerals. The modification has a field support member 61 composed of left and right hand half shells 62 and 63 that are notched to receive a supplementary magnetic yoke 64 that is snugly fitted along the sides and bottom of the member 61. The yoke 64 is disposed directly beneath the armature 37 with a small gap between each vertical leg of the yoke 64 and the armature 37 when in lower position. Yoke 64 is formed of magnetic sheet material to form a relatively low reluctance leakage flux path and its spaced relation with the other magnetic and electrical components of the electro-magnetic are shown in perspective in Fig. 10.

With the electro-magnetic switch of Figs. 1, 2 and 3 in open position the armature 37 rests upon the bottom walls 10 and excitation of the coil 15 produces leakage flux that extends through the armature 37 and thence downward and about the underside of the coil 15. An appreciable downward pull is exerted upon the armature 37 by this leakage flux the attractive force of which is in opposition to the attractive force between the armature 37 and the yoke 21. The net effect is to increase the pick-up voltage over that which would exist in the absence of such a downward pull. The relation of the coil 15 and the magnetic components comprising the yoke 21 and the armature 37 is shown in Fig. 9 to aid in a visualization of the spacing of the parts.

While the magnet of this invention ordinarily can be proportioned to provide the desired characteristics for actuating a switch without the use of supplemental yoke 64, the ease and economy with which these characteristics may be changed to meet unusual requirements by the addition or modification of supplemental yoke 64 is a further feature of value.

For example, if a given magnet constructed in accordance with this invention is arranged to actuate a switch imposing an opening bias such that applied voltage of sixty percent of normal operating voltage will cause pick-up but eighty percent voltage is required to compress the contact springs and it is desired to raise the pick-up voltage to eighty percent of normal voltage, a supplemental yoke 64 having a comparatively small cross-sectional area may be inserted. The increased counteracting attractive force produced by this yoke is effective to a perceptible degree only when the magnet is in near open position. Once the magnet starts to move, this counteracting attractive force diminishes very rapidly, becoming substantially zero when the armature has moved to a point well in advance of sealed position. By varying the cross-sectional area of the supplementary yoke 64 or its location or both, the counteracting attractive force characteristic may be varied and the pick-up voltage altered as desired. In this way it is possible to modify the magnet characteristics to meet special requirements in a very simple and economical manner.

To sufficiently demagnetize an electro-magnetic actuator so that the armature will return

5 to open position upon deenergization of the operating coil an air gap is customarily incorporated in the magnetic circuit. Since reduction of the length of the air gap may cause sticking due to residual flux, it is desirable to have the air gap unaffected by wear of the sealing surfaces. In the magnet of this invention the air gap is located wholly within the yoke 21 and is not subjected to change due to wear of the sealing surfaces and its length may be accurately set at the minimum length necessary to prevent sticking. Placing the air gap in the yoke outside of the coil is an added advantage in that less magnetizing current is required than would be required for the same gap disposed in that portion of the magnetic circuit within the coil.

10 To obtain satisfactory operation of a transversely movable armature of the type employed in this invention its movement must be guided against side play, oblique movements or tilt. To this end the external carrier 39, engaging the ends of the armature 37, slides in contact with mating surfaces on the field support member 5 disposed to compel straight line motion of the carrier 39 in which each position assumed by the armature is parallel to every other position. The wide spacing of the guide surfaces in the direction of motion aids movement of the armature assembly without binding and without concentrated stresses which could give rise to wear.

15 The housing 5 is advantageously made of electrical insulating material since such simplifies the mounting of coil 15. Where the magnet is employed for the actuation of switch contacts 33 it is also of advantage to construct the carrier 39 of electrical insulating material. Since these parts are also the main parts in sliding engagement, the organic electrical insulating materials such as the various condensed or vulcanized 20 polymers, resins and plastics are preferred, because substances of this class have excellent long wearing dry bearing properties under the type of loading imposed thereon in the apparatus of this invention.

25 I claim:

1. In an electro-magnetic actuator the combination comprising a coil having an opening extending longitudinally therethrough, a magnetic field yoke providing a flux path between the ends of said coil outside of said coil, a magnetic armature within the opening of said coil attractably movable with substantially translational motion transversely with respect to said opening toward a closed position with said field yoke upon energization of said coil and biased to move away from said closed position, a carrier joined to said armature for movement therewith, and stationary guides having guide surfaces slidably engaging said carrier adapted to guide said armature and said carrier in their translational movement toward and away from closed position.

2. In an electro-magnetic actuator the combination comprising a coil having an opening extending longitudinally therethrough, a magnetic field yoke providing a flux path between the ends of said coil outside of said coil, a magnetic armature within the opening of said coil attractably movable with substantially translational motion transversely with respect to said opening toward a closed position with said field yoke upon energization of said coil and biased to move away from said closed position, a carrier joined to each of the ends of said armature and extending about the exterior of said coil, said armature and said carrier forming an armature assembly

movable as a unit and linked with said coil, and stationary guides having guide surfaces slidably engaging said carrier adapted to guide said armature assembly upon movement of said armature in translational motion toward and away from said closed position.

3. In an electro-magnetic actuator the combination comprising a coil having an opening extending longitudinally therethrough, a magnetic field yoke extending the length of said coil along a portion of the outer surface thereof turning over and about the end faces of said coil and terminating in a pair of sealing surfaces disposed respectively at the opposite ends of said coil, a magnetic armature extending through the opening of said coil movable transversely with respect to said opening toward and away from closed position with respect to said field yoke, said armature having sealing face areas adapted to close against the sealing surfaces of said yoke, a carrier joined to the ends of said armature and extending about the outer surface of said coil to form an armature assembly with said armature, and stationary guides having guide surfaces slidably engaging said carrier adapted to guide said armature assembly upon movement of said armature toward and away from said closed position.

4. In an electro-magnetic actuator the combination comprising a coil having an opening extending longitudinally therethrough, a magnetic field yoke disposed in flux conducting relation with respect to said coil, a magnetic armature disposed in flux conducting relation with respect to said coil attractably movable transversely with substantially translational motion with respect to the opening in said coil toward a closed position with said field yoke upon energization of said coil and biased to move away from said closed position, a carrier extending around the outside of said coil connected to the ends of said armature, and stationary guides having guide surfaces slidably engaging said carrier for guided translational movement of said carrier and said armature.

5. In an electro-magnetic actuator the combination comprising a coil having an opening extending longitudinally therethrough, a magnetic field yoke extending lengthwise of and outside of said coil overhanging the ends of said coil, an armature extending through the opening in said coil attractably movable transversely with substantially translational motion with respect to said opening toward a closed position with said field yoke upon energization of said coil and biased to move away from said closed position, a carrier movable with said armature extending the length of said coil across the outer surface thereof and turning about and extending along each end of said coil to connections with said armature, and stationary guides having guide surfaces slidably engaging said carrier for guided translational movement of said armature and carrier.

6. In an electro-magnetic actuator the combination comprising a coil having an opening extending longitudinally therethrough, a magnetic field yoke extending the length of said coil along one side of the outer surface thereof and overhanging beyond the ends of said coil, a magnetic armature extending through the opening of said coil attractably movable transversely with respect to the opening in said coil toward closed position with said field yoke upon energization of said coil and biased to move away

70
75

from said closed position, a carrier movable with said armature having a cross member extending the length of said coil across the outer surface thereof and legs integrally joined with said cross member each extending respectively along an end of said coil and connected with said armature, and stationary guides having a first set of guide surfaces slidably engaging said cross member and a second set of guide surfaces spaced from said first set slidably engaging said legs.

7. In an electro-magnetic actuator the combination comprising a coil having an opening extending longitudinally therethrough, a magnetic field yoke extending the length of said coil across the top thereof and overhanging the ends of said coil, a magnetic armature within the opening in said coil movable transversely with substantially translational motion with respect to said opening to and from closed position with respect to said field yoke, a carrier straddling said field yoke having a cross member extending across the top of said field yoke and legs joined to said cross member extending downwardly beyond the ends of said coil and connected with said armature, and stationary guides having guide surfaces slidably engaging said cross member above said yoke and said legs beneath said yoke to guide said yoke and armature with substantially translational motion.

8. In an electro-magnetic actuator the combination comprising a coil having a horizontal opening extending longitudinally therethrough, a tubular non-magnetic lining extending through the opening of said coil, a magnetic field yoke disposed above said coil with end portions extending downwardly along the ends of said coil terminating in a pair of armature engaging surfaces disposed respectively at the opposite ends of said coil opening, a magnetic armature extending through said tubular lining normally resting thereon, said armature being movable transversely with respect to the opening in said coil between said position of rest and a position of engagement with said armature engaging surfaces of said yoke upon alternative deenergization and energization of said coil, a carrier movable with said armature extending the length of said coil across the outer surface thereof and the ends of said coil to connections with said armature, and stationary guides having guide surfaces slidably engaging said carrier for guided movement of said carrier and said armature.

9. In an electro-magnetic actuator the combination comprising a coil having an opening extending longitudinally therethrough, a magnetic field yoke extending the length of said coil along a portion of the outer surface thereof and overhanging the ends of said coil, said field yoke comprising a pair of closely adjacent lamination stacks spaced from one another by a small air gap transverse to field flux induced by said coil, a magnetic armature extending through the opening of said coil movable transversely with respect thereto toward and away from said field yoke member upon respective alternate energization and deenergization of said coil, a carrier joined to and movable with said armature extending the length of said coil across the outer surface thereof and about the ends of said coil to connections with said armature, and stationary guides for said carrier and said armature.

10. In an electro-magnetic actuator the combination comprising a coil having an opening

extending longitudinally therethrough, a main magnetic field yoke disposed adjacent one side of said coil, a supplementary yoke disposed adjacent the opposite side of said coil, a magnetic armature within the opening of said coil attractably movable transversely with respect to said opening upon excitation of said coil toward a closed position with said main field yoke in opposition to attractive force initially prevailing between said supplementary yoke and said armature and biased to move away from closed position toward said supplementary yoke, and a guided carrier joined to said armature for movement therewith.

11. In an electro-magnetic actuator the combination comprising a coil having an opening extending longitudinally therethrough, a magnetic main field yoke extending the length of said coil along a portion of the outer surface thereof and overhanging the ends of said coil, a magnetic armature extending through the opening of said coil movable transversely with respect thereto, said armature being adapted to move to closed position with said main yoke upon excitation of said coil and being biased to a normally open position at the side of the opening of said coil opposite said main yoke, a supplementary yoke of magnetic material disposed outside said coil adjacent the open position of said armature to provide a flux path by-passing said field yoke member, and a guided carrier movable with said armature extending the length of said coil across the outer surface thereof and along the ends of said coil to connections with said armature.

12. In an electro-magnetic switch the combination comprising a coil having an opening extending longitudinally therethrough, a magnetic field yoke providing a flux path between the ends of said coil outside of said coil, an armature of magnetic material extending through the opening of said coil movable transversely with respect to said opening toward and away from said field yoke, a carrier joined with the ends of said armature extending about the exterior of said coil, a movable contact cross bar secured to said carrier, stationary guides having guide surfaces slidably engaging said carrier and adapted to guide said armature assembly toward and away from said yoke, a plurality of movable bridging contacts mounted upon said contact cross bar, a stationary contact arc hood comprising front, back and side walls and a top wall panel, a plurality of openings in said top wall panel one of each disposed above one of said movable bridging contacts, a plurality of removable stationary contact mounting strips each detachably mounted upon said arc hood to cover one of said plurality of openings, and a pair of stationary contacts mounted on each of said mounting strips in alignment with said bridging contacts for engagement and disengagement therewith.

13. In an electro-magnetic switch the combination comprising a coil having an opening extending longitudinally therethrough, a magnetic field yoke extending the length of said coil along a portion of the outer surface thereof and overhanging beyond each end of said coil, a magnetic armature extending through and movable transversely with respect to the opening in said coil to and from closed position with respect to said yoke, a movable contact cross bar mounted on said armature for movement therewith, a plurality of movable bridging contacts resiliently mounted on said cross bar, an open bottomed arc

hood comprising front, back and side walls and top wall ribs extending between said front and back wall panels spaced from one another and said side wall panels to form a plurality of openings each disposed in line with one of said movable bridging contacts, a plurality of removable stationary contact strips each detachably mounted upon said arc hood to cover one of said plurality of openings, and a pair of stationary contacts mounted on each of said mounting strips in alignment with said bridging contacts extending from within said arc hood to the exterior to form terminals.

14. In an electro-magnetic actuator the combination comprising a coil having an opening extending longitudinally therethrough, a magnetic field yoke providing a flux path between the ends of said coil disposed outside of said coil and having armature abutting sealing surfaces adjacent the ends of said coil opening, pivotal mounting means engaging said yoke to mount the same for limited accommodating tilting movement of said sealing surfaces about an axis transverse to said coil opening, and an armature extending through said coil opening reciprocatably movable transversely with respect to the opening in said coil having seal faces engageable with said yoke sealing surfaces upon movement of said armature toward said yoke, said armature being mounted for limited accommodating tilting movement about an axis extending lengthwise thereof and perpendicular to the axis of pivot of said yoke.

15. In an electro-magnetic actuator the combination comprising a field support member, a coil having a central opening extending lengthwise thereof carried by said field support member, a magnetic field yoke providing a flux path between the ends of said coil about the outside of said coil having sealing surfaces adapted to abut an armature, a pivot mounting engaging said field yoke and said field support member supporting said yoke for limited accommodating pivotal movement, a magnetic armature within the opening of said coil having seal faces adapted to abut said sealing surfaces of said yoke and being biased to an open position with said seal faces spaced from said sealing surfaces of said yoke, said armature being attractably movable transversely with respect to the opening in said coil toward said field yoke upon energization of said coil and adapted to strike said yoke an impact blow to cause limited accommodating movement of said yoke to align said sealing surfaces with said seal faces.

16. In an electro-magnetic actuator the combination comprising a field mounting member, a coil having a central opening extending longitudinally therethrough supported by said mounting member, a magnetic field yoke extending the length of said coil along one side of the outer surface thereof and about the ends of said coil terminating in a pair of armature engaging sealing surfaces, a pivot mounting attaching said yoke to said mounting member for limited accommodating pivotal movement about an axis transverse to the coil opening, a magnetic armature extending through the opening of said coil and movable transversely thereof to and from a closed position with respect to said yoke, said armature having seal faces disposed in facing relation to the sealing surfaces of said yoke and adapted for engagement therewith upon movement of said armature to said closed position, an armature carrier connected to and movable with

said armature having a central portion extending the length of said coil along a portion of the outer surface thereof and a pair of leg portions each joined to said central portion and extending along the opposite ends of said coil, said leg portions loosely engaging and supporting said armature for limited accommodating movement permitting tilt of said armature seal faces about a longitudinal axis perpendicular to the axis of pivot of said yoke, and stationary guides slidably engaging said armature carrier guiding movement of the same transversely with respect to the opening in said coil.

17. In an electro-magnetic actuator the combination comprising a field support member having spaced rear and front walls, a bottom wall spanning the space between said rear and front walls at the lower extremities thereof, a medially disposed bridging wall spaced above said bottom wall and spanning the space between said rear and front walls to form therewith a window opening extending through said support member, said support member having a cavity extending about said window opening; a coil fitted within the cavity of said support member; a magnetic field yoke disposed adjacent said bridging wall providing a flux path between the ends of said coil about the outside of said coil; a pivotal mounting member extending through said rear and front walls and said yoke supporting said yoke; a magnetic armature extending through said window opening movable transversely with respect to said window opening toward and away from closed position with respect to said field yoke, said armature being biased to move away from said closed position and being movable upon excitation of said coil to said closed position; an armature carrier straddling said field support member and joined to the ends of said armature for movement therewith; and guides mounted on said field support member slidably engaging said armature carrier adapted to restrain said armature carrier to transverse movement with respect to said window opening.

18. In an electro-magnetic actuator the combination comprising a coil having an opening extending longitudinally therethrough, a magnetic yoke extending about the outside of said coil terminating in armature engaging sealing surfaces at the ends of said coil, a magnetic armature extending through the opening of said coil with seal faces disposed in facing relation to the sealing surfaces of said yoke forming with said yoke a working flux path, said armature being biased to an open position within the opening of said coil remote from said yoke providing when in said open position a leakage flux path linked with said coil about a segment thereof remote from said yoke establishing an attractive force upon said armature when in said open position upon excitation of said coil which is in opposition to the attractive force of flux prevailing in said yoke, said armature being movable transversely of said coil opening to a closed position with said yoke against the opposing attractive force of said leakage flux path upon excitation of said coil.

19. An electro-magnetic actuator comprising a coil having an opening, a magnetic yoke, a non-magnetic field support member supporting said coil and yoke in such position that said yoke partially surrounds said coil, a magnetic armature extending through the opening in said coil, and a slide member engaging said armature slidably related to said frame to allow movement

of said armature with substantially translational motion transversely to the opening in said coil to complete the magnetic circuit of said yoke.

20. An electro-magnetic actuator comprising 5 a non-magnetic field support member, a coil having an opening mounted upon and surrounded by said field support member, a slide member slidably related to said field support member to allow movement of said member transversely to the opening in said coil, a magnetic yoke mounted on said field support member in such position that said yoke partially surrounds said coil, and a magnetic armature extending through the opening in said coil mounted on said slide member to allow movement of said armature transversely to the opening in said coil to complete the magnetic circuit of said yoke.

21. An electro-magnetic actuator comprising 20 a field support member of insulation material enclosing a coil having an opening therein, said field support member having an opening concentric with the opening of said coil, a carrier supported and guided by said field support member, a field piece providing a flux path exterior to said coil between the ends of said opening, and an armature extending through said opening in the field support member and connected to said carrier whereby on current flow through said coil said armature will be attracted toward said field piece to actuate said carrier.

22. In an electro-magnetic actuator a coil having an opening therethrough; a non-metallic housing for said coil having an opening aligned with the opening in said coil, stationary armature 35 guiding surfaces, and a mounting shoulder; a field member extending lengthwise of the exterior of said coil and housing overhanging the ends thereof and abutting the mounting shoulder of said housing; a transversely movable armature including movable guiding means slidably engageable with said stationary guide surfaces, extending through the opening in said coil, and adapted to abut the overhanging ends of said field member when the latter is in mounted position, said armature being insertable within the opening in said coil and housing prior to the mounting of said field member; and fastening means engaging said field member and said housing mounting shoulder to secure said field member in mounted position in relation to said housing and to limit the excursion of said armature to a path precluding disengagement of said movable guiding means from said stationary guiding surfaces.

23. An electro-magnetic actuator comprising a field support member of insulating material having an opening, a coil mounted in said field support member and surrounding said opening, a carrier member of insulating material slidably related to said field support member to allow said carrier member to move transversely to said opening, a magnetic yoke mounted on said field support member in such position that said yoke partially surrounds said coil, a magnetic armature mounted in said carrier member and extending through said opening to allow movement of said armature transversely to said opening to complete the magnetic circuit of said yoke.

24. An electro-magnetic actuator comprising a field support member of insulating material having an opening, a coil mounted in said field support member and surrounding said opening, a carrier member of insulating material slidably related to said field support member to allow said carrier member to move transversely to said

15

opening, a magnetic yoke mounted on said field support member in such position that said yoke partially surrounds said coil, said magnetic yoke having an interruption providing a high reluctance gap exterior to said coil, a magnetic armature mounted in said carrier member and extending through said opening to allow movement of said armature transversely to said opening to complete the magnetic circuit of said yoke.
